BOTTLE VENDING MACHINE

Carl V. Rice, Parsons, Kans.

Application February 17, 1938, Serial No. 190,974

1 Claim. (Cl. 312—36)

This invention relates to a selective bottle vending machine particularly designed for dispensing bottled beverages of different kinds, upon the depositing of a coin in the machine.

5 The principal object of the invention is the provision of a vending machine wherein the articles to be vended may be selectively positioned relative to the delivery opening and then made accessible upon depositing a coin in the 10 machine and moving the closure, for the delivery opening, to the open position.

Another object of this invention is the provision of means to prevent the rotation of the article carrier when the parts are positioned to 15 permit the removal of one of the bottles.

Other objects are simplicity and economy of construction, ease of operation, and adaptability for use in dispensing bottles of different heights and diameters.

20 Reference will now be had to the drawings wherein:

Figure 1 is a central transverse section of a selective bottle vending machine embodying this invention.

25 Fig. 2 is a segmental plan view of certain of the operating parts.

Fig. 3 is a plan view partially broken away, of the bottle carrying rack.

Fig. 4 is a vertical section taken on line 30 IV—IV of Fig. 2.

Fig. 5 is an elevation of the coin mechanism and some of the associated parts.

Fig. 6 is an enlarged sectional view showing certain of the coin operating parts.

35 Fig. 7 is a perspective view of the operating pawl.

Fig. 8 is an enlarged sectional view taken on line VIII—VIII of Fig. 5.

Fig. 9 is a perspective view of a portion of the 40 coin operating slide bar; and,

Fig. 10 is an enlarged fragmentary view of dog 112 and its associated parts.

Throughout the several views like reference characters refer to similar parts and the numeral 10 designates a refrigerating container having insulated side walls 12, bottom 14 and an open top provided with a fixed cover member 16, having a delivery opening 18 adjacent one side thereof, and a hinged closure 20. This container is adapted to receive a refrigerant, such as ice, to maintain the vendible articles contained therein, at a desirable temperature.

Mounted for horizontal rotation in container 10 is an article carrier or rack 22, comprising a 55 series of vertically spaced apart discs 24, 26, 28

and 30, concentrically mounted on spindle 32, which is vertically disposed and mounted in an opening 34 formed in cross bar 36, which is carried by side walls 12.

Discs 24, 26 and 28 are each provided with two concentric series of bottle receiving wells 38 produced by forming concentric, circular openings 39 through said discs, whereby a bottle B may be vertically disposed therein with the bottom thereof, resting on the lower disc 30. Disc 10 30 is slidably mounted on spindle 32 for vertical movement so as to properly position bottles of different heights. The set screw 40 in hub 42 of disc 30 serves to secure the disc in fixed relation to the spindle. Bottles positioned in the two series of wells are adapted to be rotated to pass directly beneath the delivery opening 18, which is in radial alignment with the axis of rotation of the article carrier.

In some instances, bottles of different heights and diameters are vended in the same machine, and it becomes necessary to make provision for maintaining the tops of all bottles in substantially the same horizontal plane. In Fig. 1, it will be noted that a pop bottle B is shown at the left and a milk bottle M, at the right. It will also be noted that the openings 39 in discs 24 and 26 are of a diameter slightly larger than the diameter of the pop bottle and substantially the same size as the diameter of the milk bottle. The opening 39 in disc 28 is slightly smaller than those in 24 and 26, and will snugly receive the lower end of bottle B but will preclude the insertion of bottle M, thus when bottle M is positioned in the article carrying member, it will rest on the intermediate disc 28 while the longer bottles B will rest on the bottom plate 30. When so positioned, the tops of the bottles will be in substantially horizontal alignment.

The upper end of spindle 32 terminates in a 40 socket 44 having an axially disposed opening 46 and a diametrically positioned slot 48 into which the lower end of operating rod 50 and a transversely disposed key 52 respectively engage. This operating rod 50 extends upwardly through 45 a plate 54 mounted on top of cover member 16, and is provided at its upper end with an operating hand-hold 56. By simply grasping 56 and turning the same, the article carrying rack will be rotated to move the bottles contained therein, below the delivery opening where they are visible through the transparent window 58 in closure 20. By this means, it is very evident that any bottle in either of the series of wells may be moved to the delivery position at the 55

will of the operator. When so positioned, they may be delivered from the machine, as herein-after explained.

The closure 20 is hinged at 60, and is provided with an integral radially disposed lug 62 to which is pivotally secured an operating bar 64. The outer end of operating bar 64 is pivotally connected with a slide bar 66 so that as the door is moved to and from the open position, 10 said slide bar will be reciprocated through a definite path of travel.

In order to prevent rotation of the article carrier through the delivery opening when the closure is moved to the open position, the following mechanism is provided:

A notched wheel 68 is securely attached to operating rod 50 just above the plate 54. The notches in 68 are equally spaced to correspond with the relative spacing of the bottles contained 20 within the carrier. An arm 70 pivotally mounted at 72 to plate 54, extends forwardly in substantially tangential relation with the periphery of wheel 68 so that the tooth 74 positioned on the underside thereof, will register 26 with the notches 76 in wheel 68. The pivoted arm 70 is provided with an irregular cam slot 78 into which is fitted a pin 80 carried by the operating bar 64. Pin 80 is so related to the cam slot 78 that when the closure 20 is in the 30 closed position, arm 70 will be in the raised position and tooth 74 will be out of engagement with notches 76.

When the closure 20 is slightly raised, and before it would be possible to remove a bottle 35 through the delivery opening, the pin 80 will engage the quick acting portion 82 of cam slot 78 so as to lower arm 70 and position tooth 74 in one of the notches 76. The tooth 74 is slightly tapered at its end portion, as are also the teeth 40 formed between the notches 76 thereby facilitating easy insertion of the tooth in said notches whenever any one of the selected bottles is in proper alignment with the delivery opening. Should the bottle be slightly out of alignment, 45 the action of tooth 74 would tend to slightly rotate the carrier and properly position the bottle for delivery. It will be observed that the arc spacing of each of the notches 76 is identical with the arc spacing of the wells for receiving the 50 bottles thereby insuring a registering of the bottle with the delivery opening regardless of sequence of delivery.

The inner portion 84 of cam slot 78 is so constructed as to maintain the tooth 74 in a fixed 55 position relative to notches 76 during the major portion of the opening and closing operation of closure 20.

The closure 20 is normally held in the closed position by means of a mechanism releasable by 60 means of a coin deposited therein. The slide bar 66 is provided with longitudinal slots 86 through which extend the guide pins 88 which are secured to the coin slot housing 90. This slide bar is normally urged to its outer position by means 65 of a spring 92 which is attached to slide bar 66 at 94 and to plate 54 at 96. This spring 92, due to the interconnected relation of slide bar 66 with operating bar 64 and closure 20, tends to normally maintain said closure in the closed position.

Gravity pawl 98 normally rests against the ratchet tooth 100 formed in the upper edge portion of slide bar 66 to maintain the closure 20 in its closed position. Pawl 98 is provided at its free end with offset end portions 102 and 104, 102 being in alignment with the upper portion of slide

bar 66 and end portion 104 being positioned at the side thereof, and adapted to engage the periphery of a coin 106 deposited in the recess 108 formed on the inner side of slide bar 66.

As clearly shown in Fig. 6, the pawl end portion 104 is so positioned relative to the deposited coin that it will rest against the periphery of said coin and be raised upwardly as the slide bar 66 is moved rearwardly by the action of the closure 20, so as to lift the end portion 102 of pawl 98 10 from its engagement with ratchet tooth 100 so that slide bar 66 may be moved inwardly to permit the opening of closure 20. Provision is made for preventing a partial movement of slide bar 66 in one direction and return. In other words, 15 when bar 66 has been moved a sufficient distance to allow closure 20 to be opened far enough to permit the removal of a bottle, bar 66 cannot be moved backwardly until it has reached the end of its normal path of travel. This is accomplished by means of the following mechanism:

A series of notches 110 are formed on the top edge of slide bar 66 and are adapted to be engaged by means of a dog 112 which is normally held in the vertical position by means of a tension 20 spring 114. When the bar 66 is in the outward position, the dog 112 is positioned beyond the inner end of the series of notches and as the bar is moved inwardly, dog 112 will be tilted so that one corner thereof will drop into the different 30 notches of the series, see Fig. 10, so as to preclude any reverse movement of bar 66 until the bar has been moved a sufficient distance for dog 112 to clear said notches and again be positioned vertically so that when movement of bar 66 is 35 reversed, dog 112 will be tilted in the reverse direction and ride over the notches to prevent a reverse movement of said bar until it has reached the end of its inner stroke. This mechanism precludes any possible chance of obtaining the 40 delivery of a bottle and reversing the machine before it has been fully operated in an effort to obtain another bottle without depositing a second coin.

In order to prevent undue slack movement of 45 the slide bar 66, due to the fact that dog 112 requires a slight distance to right itself after leaving the series of notches 110, a tooth 116 is provided in advance of tooth 100. This tooth 116 is spaced apart a sufficient distance from 50 tooth 100 to insure the righting of dog 112 while pawl projection 102 is in position to engage tooth 116. This mechanism together with the pawl and associated notches, will insure a constant 55 control of the direction of travel of slide bar 66 and preclude any possible chance of continuous 60 operation of the closure 20 to permit the delivery of more than one bottle for each coin inserted.

The coin slot housing 90 is of a standard type 60 provided with a slot 118 into which the coin is deposited and permitted to fall by gravity until it is positioned in recess 108 where it rests on ledge 120, thereby giving it a solid foundation 65 during the time that pawl 98 is being moved to the raised position. As slide bar 66 is moved inwardly, coin 106 will be moved inwardly to register with slot 122, through which it will be delivered to any suitable receptacle. Any of the 70 well-known devices for detecting slugs, etc., may be included in the coin slot.

The mechanism carried by plate 54 with the exception of the closure 20, will be suitably 75 covered to prevent any tampering therewith.

In the operation of this machine, the customer grasps the hand-hold 56 and rotates the article carrier until the article desired is positioned directly below the transparent window 58. He 5 then drops a coin in coin slot 118 and lifts the closure 20 by means of the finger hold 124. The coin will be lodged in recess 108 and resting on ledge 120 so that as the coin is moved rearwardly, it will engage portion 104 of the dog 98 to 10 prevent the engagement of teeth 100 and 116 by pawl end 102, thereby permitting a free movement of the door to the fully open position. Upon releasing said hand-hold, the closure 20 will be returned to its closed position by the action 15 of spring 92, then the machine will be in position for another similar operation.

It is apparent that by the use of this machine a customer may first select the desired article from a plurality of articles by merely rotating 20 the article carrier. Furthermore, during the delivery of said selected article, the carrier will be definitely locked against rotation to prevent the removal of more than one bottle at each opening of the closure.

25 Having thus described the invention, what is

claimed as new and desired to be secured by Letters Patent is:

In a machine of the character described a container having a dispensing opening in the top thereof; an article container mounted for normal free rotation on a spindle in said container; an operating rod operatively interconnected with said spindle and extending outwardly from said container, whereby it may be manually operated to rotate said article container to selectively position articles carried on said article container in alignment beneath said dispensing opening; a closure member hinged to said container and normally secured in closed position with respect to said dispensing opening; coin 15 control means operable by said closure member during the first portion of its movement toward the open position to first release said closure member and to secure said operating rod against movement; and means associated with and operable by said first named means to prevent the closing of said closure member until it has been first moved to a predetermined fully open position.

CARL V. RICE. 25
